STUDIO LOUNGE

Ulysses Bruce McMurtry, Toronto, Ontario,
CanadaApplication October 17, 1935, Serial No. 45,482
In Canada October 18, 1934

4 Claims. (Cl. 5—43)

The present invention relates to a lounge with a hinged back, which is adapted, when the said back is placed in an upright position, to support a cushion or mattress thereupon, and when the back is revolved on its hinges to a horizontal position, same is adapted to lie across the top of the lounge and embrace the mattress which is normally used to cover the lounge itself.

The specific nature of the lounge and its hinged back will be more fully brought out as the specification proceeds herein.

In the accompanying drawings forming part of the present specification is shown the lounge with its hinged back, in which:—

15 Figure 1 is a partial plan view of the lounge and back, forming the subject of this invention.

Figure 2 is a vertical transverse section on line 2—2 of Figure 1.

Figure 3 is a rear elevation of a portion of the lounge shown in Figure 1.

20 Figure 4 is an enlarged detail of the means used to support the back in a vertical position taken on line 4—4 of Figure 1.

Figure 5 is a side elevation of the means used 25 to support the back, taken from the left side of Figure 1.

Figure 6 is a vertical transverse section of a channel used and its hinged connection to the frame of the lounge, taken on line 6—6 of Figure 1.

30 Figure 7 is an enlargement of a portion of Figure 2, taken on line 2—2 of Figure 1.

Figure 8 is an enlarged horizontal section taken on line 8—8 of Figure 4.

35 In the drawings, Figures 1 to 8 inclusive illustrate a means for supporting the hinged back 1, to the frame 8 of the lounge 6 comprising a pair of metal castings 2, 2.

With reference to the Figures 1 to 8 inclusive, 40 it will be seen that the lounge 6 comprises a pair of lounge ends 7, 7 which are joined by a lounge frame 8, comprising a pair of longitudinal stringers 9, 10 and a pair of opposed transverse stringers 11, 11. The lounge 6 is also provided 45 with a bed-spring 36 of any desirable form, mounted on the frame 8.

Beneath the frame 8 of the lounge 6 is shown in Figures 2 and 3 a second lounge frame 12 having foldable ends 13 adapted to be slid beneath the frame 8, and between the opposed transverse ends 7, 7 of the lounge 6.

The nature of the back member 1, and its connections is as follows: A pair of opposed vertical bars 15, 15 are rigidly mounted on the 55 pair of metal castings 2, 2 and said castings in

turn are rigidly mounted on a channel shaped member 16, which last is hingedly mounted at 17, 17 etc., to downwardly projecting straps or bars 18, 18 etc. Said straps 18, 18 are mounted rigidly on the longitudinal stringer 9, as is at 5 once understood. It is apparent that the back member 1 may be swung on its hinges 19, 19 etc., from the vertical position 20, Figure 2 to the horizontal position 21 shown dotted therein, and the width of the web of the channel 16 is selected 10 so that when the back member is in a horizontal position, the latter will embrace and cover the frame 8 and lie beneath the mattress or cushion 22, which normally lies upon the frame 8 of the lounge 6, and will also be of sufficient width 15 to support the cushion 23, in a vertical position between the vertical bars 15, 15 and the longitudinal stringer 9 of the lounge, as clearly illustrated in said Fig. 2. Small cushions 24, 24 etc., may be used and placed against the mattress 23 20 if desired as illustrated in Fig. 2.

The nature of the castings 2, 2 may be seen from Figures 1, 4, 5, 7 and 8 of the drawings in which 25 indicates a short vertical leg, and 26 a longer vertical leg which last furnishes the means of supporting the vertical bars 15, 15 of the back member 1. The vertical legs of the castings are joined by the web member 27. A projecting flange 28 is formed on the edge of the vertical leg 26, and extends along the edge of the web 27 of the castings 2, 2 same being used to strengthen the castings, as well as to form an abutment for the edge of the vertical bars 15, 15 and the end of the channel 16, as is at once 35 understood.

The shorter vertical leg 25 as well as the flange 28, and a portion of the web 27 are cut away at 30 for the purpose of permitting the flange 30 of the vertical stop angle 31 to become operatively 40 engaged with the outstanding portion 32 of the castings 2, 2 when the back is in a vertical position, and the part 32 thus forming a stop, and a support for the back member 1.

When the back member 1 is thrown forward 45 as shown in Figure 2 to approach the horizontal position 21, the stop angle 31 is at once disengaged from the outstanding portion 32 of the vertical leg 25 of the castings 2, 2. It will be noted that the vertical legs 25 of the castings, 50 as seen in Figs. 4 and 8 clearly, extend further to the left than the edge or flange 28 of the casting 2 for the purpose of permitting the engagement of part 32 with flange 30 as above described. The stop angle 31 is rigidly mounted at 55

33, 33 on the lounge ends, as seen in Figs. 1, 4, 7 and 8 clearly.

The lower lounge member 12 is provided with rollers 34, 35 to act as guides when the same is being inserted between the lounge ends 1, 1 and it will be seen in Fig. 2 that the bottom portion of the angles 31, 31 act as stops for the member 12. Rollers 37, 37 are also provided beneath member 12 to enable same to be rolled into position under the lounge frame 8.

The back member 1 may be provided with a series of flat straps 38, 38 etc., which are yieldingly attached by means of springs 39, 39 etc., to the vertical bars 15, 15. These straps form a support when used for the cushion 23. The vertical bars 15, 15 are joined together at their upper ends by a preferably tubular member 58.

The manipulation of the device in hand may be briefly described as follows:

20 The cushion 23 Fig. 2 is normally lodged in the channel 16, and rests against the back member 1, and the small cushions 24, 24 rest against said cushion 23 while the cushion or mattress 22 is mounted on the frame 8 of the lounge 6. When 25 it is desired to use the lower lounge, frame 12 is withdrawn from between the lounge ends 1, 1 and its ends 13, 13 are placed in an upright position (not shown) the cushion 23 is removed from the lounge 6 and placed on the top of the lower lounge 12. The back 1 is then swung on its hinges to a horizontal position 21 over the frame 8 of the lounge 6 and the mattress 22 is placed thereupon, completely hiding the back from view. When it is desired to have the cushion 35 23 in the position shown in Fig. 2 as above described, the portion 32 of the leg 25 of the castings 2, 2 is placed in engagement with the flange 30 of the stop angles 31, 31 and gives support to the said back member 1, as is readily understood.

40 I claim:—

1. In a lounge with a hinged back, a lounge frame, a pair of lounge ends mounted on the frame, a stop-angle on each lounge end, a back-member for the lounge, a channel forming part 45 of the lounge back, pivotally connected to the rear of the lounge frame a substantial distance below the top of same, said channel being of sufficient width to permit the insertion of a cushion

between the back-member and the frame, and adapted to permit the back-member to embrace the top of the frame when the back-member is placed in a horizontal position, and a U-shaped casting mounted on each end of the channel, each adapted to engage the outstanding leg of each stop-angle for the purpose of supporting the back-member when same is in a vertical position. 5

2. In a lounge with a hinged back, a lounge frame having a pair of opposed lounge ends thereon, a stop-angle on each lounge end, a back-member having a channel thereon hingedly mounted on the rear of the lounge frame, a U-shaped casting on each end of the channel, having an outwardly projecting leg adapted to 10 engage the outstanding leg of one of the stop-angles and prevent revolution of the back member in one direction when the latter is in a vertical position.

3. In a studio lounge having a pair of ends and a hingedly mounted back thereon, a stopping device comprising a stop angle mounted on each of the lounge ends, and a casting on each end of the lounge back, consisting of a long and a short leg, a web-member connecting said legs, and an 20 outstanding portion formed on the shorter leg projecting beyond the edge of the web-member, adapted to engage one of the stop angles, and act as a support for said back, when the latter is in a vertical position. 30

4. In a lounge having a frame, a pair of lounge ends, and a hinged back; a channel forming part of the lounge back, connected to the rear of the lounge frame a substantial distance below the top thereof, and of sufficient width to permit the back to embrace the top of the frame when the back is placed in a horizontal position, and a stopping device comprising a stop-angle mounted on each of the lounge ends, and a casting on each end of the lounge back, consisting of a long 40 and a short leg, a web-member connecting said legs, and an outstanding portion formed on the shorter leg projecting beyond the edge of the web-member, adapted to engage one of the stop angles and act as a support for said back, when the latter is in a vertical position. 45

ULYSSES BRUCE McMURTRY.
